UNITED STATES PATENT OFFICE.

EDWARD A. ROSENBERG, OF NEW YORK, N. Y.

DESIGN FOR AN ATOMIZER HEAD.

Application filed May 21, 1925. Serial No. 13,529. Term of patent 14 years.

To all whom it may concern:

Be it known that I, EDWARD A. ROSENBERG, a citizen of the United States, residing at New York, N. Y., have invented a new, original, and ornamental Design for Atomizer Head, of which the following is a specification, reference being had to the ac-

companying drawing, forming part thereof.

The figure is a side elevation of an atomizer head, showing my new design as used.

I claim:

The ornamental design for an atomizer head, substantially as shown.

EDWARD A. ROSENBERG.
